UNITED STATES PATENT OFFICE.

THOMAS H. WALKER, OF WALLACE, IDAHO.

CURRENT-MOTOR.

1,346,285.

Specification of Letters Patent. Patented July 13, 1920.

Application filed October 16, 1918. Serial No. 330,995.

To all whom it may concern:

Be it known that I, THOMAS H. WALKER, a citizen of the United States, residing at Wallace, in the county of Shoshone and State 5 of Idaho, have invented certain new and useful Improvements in Current-Motors; and I do declare the following to be a full, clear, and exact description of the invention, such as will enable others skilled in the art to 10 which it appertains to make and use the same.

This invention relates to current motors, and more specifically to a form of water motor.

15 One object of this invention is to generally improve upon devices of this character by providing an improved structure which may be conveniently placed on the sloping bank of a stream of water, and which is 20 exceedingly durable and practical consistent with comparative cheapness or slight cost to manufacture and install.

Other objects and advantages may become apparent to persons who read the following 25 details of description in connection with the accompanying drawings in which:—

Figure 1 is a perspective view of the complete device installed near a stream of water. Fig. 2 is a vertical sectional view through 30 the axis of the device.

Fig. 3 is a plan view of the hub or rotary plate through which the arms are pivotally connected.

Fig. 4 is a perspective detail view illustrating one of the buckets in the position just prior to that in which it is opened for discharging water therefrom.

Fig. 5 is a view similar to Fig. 4 except that the bucket is in the position for discharging the water into a trough or receiver.

Fig. 6 is a view similar to Figs. 4 and 5 except that the bucket is in the position just prior to that in which it is closed.

Fig. 7 is a view similar to Fig. 6 except 45 that the bucket has been closed by a closing element mounted on the trough or receiver.

Referring to these drawings in detail, in which similar reference characters correspond with similar parts throughout the several views:—

A foundation 1 of cement is located on the sloping bank of a river which is indicated by the arrow, or rather the current of the river is indicated by the arrow at the 55 lower portion of Fig. 1. A track of metal

is indicated at 2, and this track is preferably embedded in or secured to the foundation 1, although it may be supported by any appropriate means. The track 2 is circular and slopes toward the river or current of 60 water. A pivot or axis 3 is anchored in the foundation 1 and extends upward through a central opening or bearing in the hub 4 which is indicated separately in Fig. 3. Rollers or casters 5 are secured to the 65 hub 4 and travel on the track 2, and it will be seen, therefore, that the hub 4 rotates about the axis 3, being supported by the wheels or casters 5.

Any appropriate number of arms or 70 sweeps 6, preferably an even number, are pivotally connected at 7, to bearings 8, the latter being of any appropriate form and being secured to the hub 4 or formed integrally therewith according to the preference 75 of the manufacturer. The pivotal connections 7 are such as to prevent movement of the arms 6 with relation to the hub 4 except about the axes of the rods or pivot elements 7. 80

Each of the arms 6 has a roller 9 secured thereon, and the rollers 9 travel on a cam or guide 10, the latter being curved around the hub 4 and being upwardly inclined from the brink of the stream or water current. 85 Moreover, the inclination of the member 10 is greater than that of the track 2, as clearly shown in Fig. 2, so that as the rollers 9 pass upward along the track 10, they are thrown upward about their pivots 7 into the upright 90 position shown in Fig. 2.

Each arm 6 carries a combined paddle and bucket 11 which is adapted to discharge water into a trough or receiver 12, the latter being located at a level considerably 95 above that of the highest point of the track 10. The buckets 11 are of the improved construction shown more particularly in Figs. 4 to 7 inclusive. Each bucket 11 is provided with an inlet or opening 13 and with 100 an outlet 14. A valve or outlet closer 15 is hinged or otherwise loosely connected at 16 to each bucket 11, and a spring catch 17 is engageable with the member 15 for holding it in the closing position. The spring catch 105 17 is provided with an outward projection 18 which is adapted to engage with a cam or downwardly inclined rod 19 during movement of the buckets over the trough 12, so as to lower the catch 17 and release the 110
